[57] CLAIM

The ornamental design for a towel holder, as shown and
described.

DESCRIPTION

FIG. 1 is a top front and right side perspective view of
a towel holder showing my new design;

FIG. 2 is a front elevational view thereof;

FIG. 3 is a right side elevational view thereof, the left
side being a mirror image of that shown;

FIG. 4 is a rear elevational view thereof;

FIG. 5 is a top plan view thereof; and

FIG. 6 is a bottom plan view thereof.

Fig. 1.

Fig. 2.

Fig. 3.

Fig. 4.
